Primary Examiner—Wallace R. Burke*Assistant Examiner*—Marcus Jackson*Attorney, Agent, or Firm*—Charles H. Thomas**[57] CLAIM**

The ornamental design for crushable traffic marker, as shown and described.

DESCRIPTION

FIG. 1 is a front perspective view of a crushable traffic marker in its extended condition as employed for operation showing my new design;

FIG. 2 is a top plan view thereof;

FIG. 3 is a front elevational view thereof, it being understood that the rear and both side elevational views are identical thereto;

FIG. 4 is a bottom plan view thereof; and,

FIG. 5 is a front perspective view thereof shown in a collapsed condition.
